DESIGN FOR A BELT BUCKLE

Jerome R. Lavigne, Waterbury, Conn., assignor to
The Waterbury Buckle Company, Waterbury,
Conn., a corporation of Connecticut

Application November 4, 1935, Serial No. 59,372

Term of patent 3½ years

To all whom it may concern:

Be it known that I, Jerome R. Lavigne, a citizen of the United States and residing at Waterbury, in the county of New Haven and State of Connecticut, have invented a new, original, and ornamental Design for a Belt Buckle, of which the following is a specification, reference being had to the accompanying drawing, forming part thereof.

Fig. 1 is a plan view of the belt buckle, showing my new design.

Fig. 2 is an edge view of the same.

I claim:

The ornamental design for a belt buckle as shown.

In testimony whereof, I have affixed my signature to this specification.

JEROME R. LAVIGNE.
